UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,093, dated September 22, 1896.

Application filed August 5, 1896. Serial No. 801,828. Term of patent 3½ years.

To all whom it may concern:

Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.

10 The design consists of an arrangement of ornamental scrolls forming large shield-shaped panels or ornaments with a series of vertical parallel stripes inside of said panels or ornaments and ornamental scrolls interlacing with 15 said panels or ornaments, as represented in the accompanying drawing.

The border for said design is also formed of similar shield-shaped ornaments or panels formed of ornamental scrolls with vertical parallel stripes inside of said panels and ornamental scrolls diverging right and left from each side of said ornaments or panels and connected by ornamental figures, as shown in the drawing. 20

What I claim is— 25

1. The design for wall-paper herein shown and described.
2. In the design for wall-paper the border herein shown and described.

Witness my hand this 1st day of August, 30 1896.

CHARLES BOOZ.
